Primary Examiner — Marissa J Cash(74) Attorney, Agent, or Firm — Karceski IP Law, PLLCCLAIM

The ornamental design for a galley, as shown and described.

DESCRIPTION

FIG. 1 is a perspective view of a first embodiment of a galley according to the design;

FIG. 2 is a front view of the galley of FIG. 1;

FIG. 3 is a right side view of the galley of FIG. 1;

FIG. 4 is a left side view of the galley of FIG. 1;

FIG. 5 is a top view of the galley of FIG. 1;

FIG. 6 is a bottom view of the galley of FIG. 1;

FIG. 7 is a perspective view of a second embodiment of a galley according to the design;

FIG. 8 is a front view of the galley of FIG. 7;

FIG. 9 is a right side view of the galley of FIG. 7;

FIG. 10 is a left side view of the galley of FIG. 7;

FIG. 11 is a top view of the galley of FIG. 7; and,

FIG. 12 is a bottom side view of the galley of FIG. 7.

The broken lines that are included in the figures of the drawings denote aspects of the galley that form no part of the claimed design.

1 Claim, 12 Drawing Sheets(56)
